[57] CLAIM

Ornamental design for a combined pepper mill and salt shaker, as shown and described.

DESCRIPTION

FIG. 1 is a perspective front view of a combined pepper mill and salt shaker showing my new design;
 FIG. 2 is a top plan view thereof;
 FIG. 3 is a front elevational view thereof;
 FIG. 4 is a left side elevational view thereof;
 FIG. 5 is a right side elevational view thereof;
 FIG. 6 is a bottom plan view thereof;
 FIG. 7 is a front perspective view of a second embodiment of that shown in FIG. 1;
 FIG. 8 is a top plan view of that shown in FIG. 7; and
 FIG. 9 is a front elevational view of that shown in FIG. 7.
